UNITED STATES PATENT OFFICE.

FLORIAN ROHACH, OF CHICAGO, ILLINOIS.

DEVICE FOR GRINDING MOWER-KNIFE SECTIONS.

SPECIFICATION forming part of Letters Patent No. 761,406, dated May 31, 1904.

Application filed March 12, 1904. Serial No. 197,761. (No model.)

To all whom it may concern:

Be it known that I, FLORIAN ROHACH, a citizen of the United States of America, and a resident of Chicago, in the county of Cook and State 5 of Illinois, have invented certain new and useful Improvements in Devices for Grinding Mower-Knife Sections, of which the following is a specification.

The main objects of my invention are to provide an improved form of grinding-carriage particularly adapted for grinding knife-sections of mowing machinery; to provide a device of this class which may be readily adjusted for grinding knife-sections of varying 15 forms and which may be readily adjusted for grinding any desired bevel on the cutting edges of the sections; to provide in a carriage of this class means for holding the knife-section against a grindstone with a uniform pressure and adapted to readily yield when passing irregularities on the surface of the stone, thus avoiding irregular grinding and the consequent drawing of the temper of the knife-section; to provide a clamping device which 20 will quickly grip and release the knife-sections, and thus permit of the rapid grinding of the same, and which may be quickly readjusted for grinding sections differing considerably in form. I accomplish these objects by 25 the device shown in the accompanying drawings, in which—

Figure 1 is a front elevation of a grinding-carriage constructed according to my invention, one of the clamp members being removed 35 for the purpose of showing the conformation of the face-plate. Fig. 2 is a rear elevation of the same. Fig. 3 is an end elevation of the same, showing, partly broken away, the grindstone and certain portions of the frame 40 of the grindstone and the runway of the carriage. Fig. 4 is a side elevation of one of the yielding supporting-hooks of the face-plate. Fig. 5 is a side elevation of the adjusting-hook for adjusting the inclination of the face-plate. Fig. 6 is a top plan of the yielding back brace for the face-plate. Fig. 7 is a front elevation of one of the clamp members which is mounted on the face-plate. Fig. 8 45 is a rear elevation of the same. Fig. 9 is a view showing one of the usual forms of knife-

sections for the grinding of which the device herein shown is particularly constructed, the dotted lines indicating the position of adjacent sections of the knife.

In the construction shown the grindstone 1 is journaled on a horizontal axis in the frame 2. The frame of the grindstone is provided with a level runway 3, along which the grinding-carriage 4 may be moved in a forward and backward direction across the face of the 55 grindstone. A pair of guide-rollers 5 is journaled on the carriage and bears upon the guide-rail 6 for guiding the carriage in a direction parallel with the axis of the grindstone 1. The carriage rides upon four rollers 7. A face-plate 8 is mounted on the side of the carriage 4 which is nearest to the grindstone 1. The face-plate 8 is rounded at 9 near the ends of its lower edge and rests on two supporting-hooks 10, which are connected with 60 the frame 4 of the carriage and provided with springs 11, so as to yieldingly support the face-plate 8. The face-plate 8 is adjusted in a vertical angle on its supporting-hooks 10 and is prevented from tilting forward by means of the hook 12, which extends around the lower end of the face-plate 8 and bears against its front face, as shown in Fig. 5. The face-plate 8 is adjusted angularly by means of the nut 13 on the shank of the hook 12, which 65 bears against the rear side of the carriage 4. The plate 8 is normally held in a forwardly-inclined position by means of the back brace 14, which is connected with a lug 15 on the carriage and normally urged in a forward direction by means of the spring 16, the tension of which is adjusted by the nut 17. The upper edge of the face-plate 8 is provided with a straight edge 18, which serves as a guide for lining up the edge of the knife-section 19 70 while the clamps are being adjusted for sections of that particular shape.

A pair of clamp members 20 are mounted on the front face of the face-plate 8. These are preferably in the form of sectors provided 75 with pivots 21, which fit apertures 22 in the face-plate. The sectors are adapted to be shifted angularly about their pivots 21 and are secured in any position of adjustment by means of the bolts 23, which pass through 80

holes 24 in the sectors and through slots 25 in the face-plate. Ribs 26 at the sides of the slots 25 on the rear face of the plate prevent the turning of the nuts when the bolts 23 are being tightened. The bolts 23 besides securing the sectors in their position of angular adjustment also secure to the face of the same the spring-clips 27, which serve to hold the knife-sections 19 against the face of the face-plate 8. The knife-section 19 bears at one edge against a key 28, which is set in the keyway 29 of the sector, and another edge of the knife-section bears against a guide-block 29', which is adjustable on the face of the sector. A still further range of adaptability to varying forms of knife-sections may be had by exchanging the blocks 29' with others of different shape and by shifting the bolt which holds the block 29' to the slot 31.

In operation the two sectors 20 are adjusted angularly in their own plane on the front of the face-plate to conform with the angle of the cutting edges 30 of the knife-sections, each knife-section being held by one of the sectors when its right-hand edge is being ground and in the other sector when its left-hand edge is being ground. The spring-clips 27 firmly hold the knife-sections in position while the same are being ground, but readily permit of the removal or insertion of a knife-section without readjustment. In practice a section is secured upon each of the sectors, and the carriage is then pushed forward and back across the face of the grindstone, one movement in each direction being sufficient to grind both of the sections. The sections are then removed. Their positions on the face-plate are reversed, and the other edges are then ground in the same way. The springs on the hooks which support the face-plate 8, together with the spring on the back brace 14, serve to hold the sections in contact with the grindstone and with a yielding uniform pressure, the spring on the back brace permitting the section to yield transversely of its plane and the springs on the supporting-hooks permitting a slight angular yielding in the plane of the sections. It frequently happens that there are hard spots in the grindstones which do not wear as rapidly as other parts of the stone, and therefore lead to irregular surfaces. For this reason it is desirable to have a yielding support for the section, since a rigid support leads to irregular grinding on account of the irregularities in the surface of the stone and frequently draws the temper at certain points along the edge of the knife-sections. To change the device for grinding sections of different form, it is merely necessary to swing the sectors to suit the angle between the cutting edges of the new section, the straight edge 18 serving for lining up the cutting edge, and finally to shift the block 29' to suit

the size of the section. A change in the bevel of the sections is made by adjusting the inclination of the face-plate by means of the hook 12 and the back brace 14.

It will be seen that numerous details of the construction shown may be altered without departing from the spirit of my invention.

What I claim as my invention, and desire to secure by Letters Patent, is—

1. In a device of the class described, the combination of a frame; a carriage movable in a certain direction on said frame; a clamp member mounted on said carriage and adapted to hold a knife-section with one of its cutting edges in a position parallel with the path of said carriage, said clamp member being adjustable angularly for the purpose of adjusting the cutting edge of the knife-section into parallelism with the path of the carriage, substantially as described. 85

2. In a device of the class described, the combination of a frame; a carriage movable in a certain direction on said frame; a clamp member mounted on said carriage and adapted to hold a knife-section with one of its cutting edges in a position parallel with the path of said carriage, said clamp member being adjustable angularly about an axis disposed transversely of the path of the carriage, substantially as described. 95

3. In a device of the class described, the combination of a frame; a carriage movable in a certain direction on said frame; a clamp member mounted on said carriage and adapted to hold a knife-section with one of its cutting edges in a position parallel with the path of said carriage, said clamp member being adjustable angularly about an axis disposed in parallel relation with the path of said carriage, substantially as described. 100

4. In a device of the class described, the combination of a frame; a grindstone journaled in said frame; a carriage mounted in said frame and adapted to move along a path parallel with the axis of said grindstone; a clamp member secured to said carriage and adapted to grip a knife-section and hold same in suitable position to bring the cutting edge of said section into contact with said grindstone; means for adjusting said clamp member angularly for shifting said knife-section in its own plane for alining same with the surface of the grindstone; and means for shifting the plane of the knife-section for adjusting the same to suit the bevel of the cutting edge of the knife, substantially as described. 110 115

5. In a device of the class described, the combination of a carriage having rollers adapted to permit the carriage to be moved in a certain direction; a plate secured to one side of said carriage and lying in a plane parallel with the direction of movement of the carriage; a clamp member mounted on said plate and adapted to secure a knife-section to the face 120 125 130

of the plate; means for adjusting the knife-section angularly in its own plane and means for adjusting said plate in an angle transversely of the plane of the knife-section, said 5 plate being adapted to yield laterally of its own plane, substantially as described.

6. In a device of the class described, the combination of a carriage having rollers adapted to permit the carriage to be moved in a certain direction; a plate secured to one side of 10 said carriage and lying in a plane parallel with the direction of movement of the carriage; a clamp member mounted on said plate and adapted to secure a knife-section to the face 15 of the plate; means for adjusting the knife-section angularly in its own plane and means for adjusting said plate in an angle transversely of the plane of the knife-section, said 20 plate being adapted to yield edgewise in its own plane, substantially as described.

7. In a device of the class described, the combination of a carriage having rollers adapted to permit the carriage to be moved in a certain direction; a plate secured to one side of 25 said carriage and lying in a plane parallel with the direction of movement of the carriage; a clamp member mounted on said plate and adapted to secure a knife-section to the face of the plate; said clamp member being adjustable angularly in a plane parallel with the 30 face of said plate, and said plate being adjustable transversely of its own plane, substantially as described.

Signed at Chicago this 9th day of March, 1904.

FLORIAN ROHACH.
